UNITED STATES PATENT OFFICE.

WINSLOW R. PARSONS, OF CHICAGO, ILLINOIS.

SEWING-MACHINE TUCKER.

SPECIFICATION forming part of Letters Patent No. 766,840, dated August 9, 1904.

Application filed February 16, 1903. Serial No. 143,541. (No model.)

To all whom it may concern:

Be it known that I, WINSLOW R. PARSONS, a citizen of the United States, residing at Chicago, in the county of Cook and State of Illinois, have invented certain new and useful Improvements in Sewing-Machine Tuckers, of which the following is a full, clear, and exact specification.

My invention relates to tuckers for sewing-machines.

Heretofore there have been separate attachments falling under the general class of tuckers known, respectively, as "tuck-markers" and "tuck-folders," or tuckers which do not mark the goods, but simply serve to fold the same where the tuck is to be formed. The former of these operates to produce a mark or crease as a guide to the operator and is most commonly employed on white or light goods, while the latter form or tuck-folder does not mark the goods, but serves to denote the line where the goods are to be stitched by affording the operator a guide against which to place the apex of the last fold or tuck. This latter form of tucker is especially designed for that character of goods which cannot or should not be creased or marked by the tuck-marker. With the first of these forms the operation is performed with the tucked and stitched fold of the goods underneath next the knife-arm or lower smoothing-arm and the apex of the new fold or tuck against the usual adjustable gage, while the apex of the last complete tuck passes under a small lip or tuck-guide adjacent to the knife to prevent such tuck from riding over the edge of the knife during the tuck-marking operation. With the latter of these forms of tuck-folder, however, the tucked fold of the goods is arranged on top next the upper smoothing-arm and the apex of the last-finished tuck is placed against the aforesaid fold-guide on such upper smoothing-arm, while the apex of the new tuck being formed is placed against the usual gage, which denotes the distance of the new line of stitching from the last tuck. Both of these forms of tuckers require a gage and its scale, a smoothing-arm

above the goods, and an arm corresponding to the knife-arm, which also serves as a smoothing-arm below the goods even when the knife is not used. Thus where both forms are required a double expense is entailed, to say nothing of the trouble of changing and adjusting the two separate attachments.

The primary object of my invention is to combine the two attachments in one, so that it may be used at will as either a tuck-marker or a tuck-folder without removing it from the machine.

With these ends in view my invention consists in certain features of novelty in the construction, combination, and arrangement of parts by which the said object and certain other objects hereinafter appearing are attained, all as fully described with reference to the accompanying drawings and more particularly pointed out in the claims.

In the said drawings, Figure 1 is a perspective view of a tucker embodying my invention, showing it in operation on a sewing-machine. Fig. 2 is a similar view thereof, showing the tucker-arm detached from the needle-bar and held down in its inoperative position. Fig. 3 is a plan view of the tucker detached from the sewing-machine. Fig. 4 is a side or front elevation showing the tucker-arm secured in its inoperative position. Fig. 5 is a detail plan view of the knife and one end of the knife-arm. Fig. 6 is an enlarged transverse section taken on the line 6 6, Fig. 3. Fig. 7 is a vertical detail section taken on the line 7 7, Fig. 3. Fig. 8 is a detail rear elevation of the smoothing-arm with the creaser and tuck-folder thereon, showing its relation to the knife-arm and knife. Fig. 9 is a longitudinal section on the line 9 9, Fig. 3. Figs. 10 to 16, inclusive, illustrate a modified form of the invention, Fig. 10 being a plan view thereof detached from the sewing-machine. Fig. 11 is a front elevation. Fig. 12 is a vertical longitudinal section taken on the line 12 12, Fig. 10. Fig. 13 is an enlarged detail perspective view hereinafter described. Fig. 13' is a detail of the creaser. Fig. 14 is a vertical enlarged cross-section on

the line 14 14, Fig. 10. Fig. 15 is an end elevation looking from the left in Fig. 10, and Fig. 16 is an enlarged detail perspective view of the knife and end of the knife-arm.

5 1 is a flat strip or bar which constitutes the knife-arm and upon the edge of which is formed an extension 2, whose inner edge is upturned to constitute a sharp member or knife 3; and with which member or knife 3 co-
10 operates the crease notch or marker 4, arranged directly above the knife 3, as usual, and formed in the lower surface of a downwardly bent or curved portion 5 of a finger or lever having an upwardly-extending portion 6 and secured to a flexible arm or strip 7, which is marked with the usual graduations, extends over the knife-arm 1, and exerts a normal tendency to hold the crease notch or marker 4 aloof from the knife 3. The two
15 arms 1 7 may be secured together at their meeting ends in any suitable way—such, for example, as passing a lug 8 on the end of arm 7 through a lip or flange 9 on the end of bar 1 and then riveting the two bars together at
20 another point. This rivet may be constituted by the end 10 of a spring 11, which is also passed through the lip or flange 9, thereby serving the twofold purpose of holding bars 1 and 7, as well as the spring, one end of which
25 is straightened out to constitute the operating-arm 12, and which extends longitudinally of the arms 1 7 and is adapted to strike and depress the finger extension 6, and thereby produce the crease in the goods passing over the
30 knife 3. The end of the arm 12 is provided with a downwardly-extending hook 13 in order that it may better engage and operate the finger 6, and in order that the arm 12 may be thus oscillated in unison with the needle-bar
35 40 14 it is provided with a clip 15, held thereon by a pair of ears 16, so as to be capable of sliding longitudinally on the arm and provided with a hook 17, adapted to engage the needle 18 just below the needle-bar, whereby the
45 arm 12 is attached to the needle-bar and moves up and down therewith to engage and depress the finger extension 6 and arm 7 at every downward stroke of the needle. Should it be desired, however, to stop the operation of the
50 tuck-marker, the clip 15 is unhooked from the needle and slipped along the arm 12 until the hook of the clip can be engaged in an eye 19, secured to the tucker in any suitable way, as by means of the end 10 of the spring passing therethrough, the arm 7 being bent or shouldered at 7^a to prevent the eye 19 from rotating on the riveted end 10 of the spring. Upon this smoothing-arm 7 and on the lower side of the free end thereof is also mounted
55 60 the tuck-fold guide 20, which, as better shown in Fig. 8, is in direct line with the tuck marker or notch 4 and the knife 3.

21 is the screw or other suitable device for

attaching the plate to the sewing-machine plate, and the plate preferably consists of a flat strip or sheet of metal or other suitable material 22, folded upon itself, with one fold over and the other fold under the arm 1, and between which folds said arm slides, the screw 21 being passed through a slot 23 in both folds of plate 22, so as to be also utilized as a means of clamping the arm 1 in the position to which it is adjusted. The arm 1 may be held against lateral or transverse movement between the folds of the plate 22 by upturned lugs 24 or other suitable means, and the free ends of the plate 22 are secured together by a lip 25, struck up from the lower one and folded over the upper one.

26 is the tuck-gage, which serves without change as a gage for both the tuck-marker 3 and the tuck-fold guide 20, inasmuch as it bears the same relation to both. This gage 26 has a lip 27, through which passes a strip 28, secured to the plate 22 and having a suitable scale marked thereon. The gage 26 is also provided with a stem or slide 29, which passes between the folds of plate 22 and has its upper end turned up in the form of a lug or stop 30 to prevent it from being pulled out. The slide 29 is guided or held against lateral movement by lugs or flanges 31, turned up at the edges thereof from the lower fold of plate 22. The strip 28 is also held between the two folds of plate 22, and it is secured against longitudinal movement by the lugs 24 31, which overlap the edges of the strip, as shown in Fig. 3. It is also seen that the screw 21 serves as a means for clamping the slide 29 at the desired adjustment.

I will describe first the operation of the device as a tuck-marker, as shown in Fig. 1, although in the main it does not differ in such use from the operation of the ordinary tucker. The fabric is first folded upon itself and the apex of the fold placed against the gage-lip 27, the latter being set for the desired width of tuck, and the fabric is then stitched to produce the first tuck. This tuck is then drawn beneath the top fold and its apex placed under and against the usual tuck-guide lip 3^a, with the single thickness of the lower fold passing over the knife 3, while the apex of the new or main fold is placed against gage 27, after which the folds are again stitched together along the crease or mark formed by the knife and creaser to produce another tuck, and so on, the tucks being always turned under the top fold, which is plain and without either tucks or folds. When using the device as a tuck-folder, as shown in Fig. 2—that is, for folding the tucks without marking the goods—the creaser-operating arm is held inoperative by the hook 17, and the fabric is folded upon itself and placed between the upper and lower smoothing-arms

17, as before. Assuming that the tucks are to be of the same width as those produced with the tuck-marker in operation, the gage 27 is allowed to remain unchanged, and the apex of the fold is placed thereagainst, and hence the seam when run will fall the proper distance from such apex, thus producing the first tuck. This tuck instead of being drawn beneath the top fold is pulled over the bottom fold toward the left until the tuck engages the fold-guide 20, with the apex of the tuck resting in the crotch formed by such guide and the bottom of arm 7. With the first tuck thus positioned the fold of the fabric is now worked toward gage 27 until the apex of such fold rests thereagainst, whereupon the goods will be in position to be stitched, thus producing the second tuck, which is then drawn around on top and pressed against guide 20, as before. It will thus be seen that the guide 20 is necessarily positioned above the goods and not below the same, whereas the guide 3^a is necessarily below the goods.

Referring to the form of my invention shown in Figs. 10 to 16, it will be seen that the crease notch or marker 4^x is formed in the elbow 32 of a downwardly-extending arm 33 on the end of a spring-arm 12^a, which is the same in construction as the arm 12 before described; but in this instance instead of being acted on directly by the needle-bar it is acted on through the intermediary of a separate operating-arm 34, which is engaged by the needle-bar as the latter descends, and thereby causes the crease-notch 4^x to press the goods against the knife 3^x, the arm 34 being returned as the needle-bar rises by the spring-arm 12^a. The arm 34 is pivotally supported on the plate by means of a pivot 35 and a standard 36 and projects across the spring-arm 12^a; but instead of impinging the arm directly it is preferable to cause the arm 34 to do its work through the medium of a set-screw 37 or other adjustable means, so that the degree of pressure with which the crease-notch 4^x forces the goods against the knife 3^x may be varied to suit the requirements. To this end one side of arm 34 is formed with a boss 38, in which screw 37 is threaded and above which on the screw is located a jam-nut 39 for locking the screw in position. When it is desired to throw the tuck-marker out of operation, so that the crease-notch will cease to engage the goods, the arm 34 may be thrown outwardly out of the line of movement of the needle-bar by turning it on its pivot 35. In order, however, that the arm 34 will remain in the position in which it is placed, it is desirable to provide it with some suitable form of friction-hold that will permit of it being readily placed in either position. For this purpose I have shown a spring-dog 40, secured to the side of standard 36 and pro-

jecting around the edge thereof in position to engage with either of two shoulders 41 42 on the arm 34. The dog 40 may be held in place by the same pivot 35 which fulcrums arm 34, and in order that the dog may not revolve with the arm it is formed with a perforated extension 43, through which the spring-arm 12^a is passed. In this form of the invention the tuck-fold guide is constituted on the arm 7^x by two downwardly and laterally bent lips 20^a on a cross-bar 20^b, formed integrally with the arm 7^x in line with the crease marker or notch 4^x on the arm 12^a. The plate is formed, preferably, integrally with a sewing-machine presser-foot 44, provided with a bifurcated lug 45, whereby it may be attached to the presser-foot bar of a sewing-machine in the well-known manner. The presser-foot 44, however, is cut off short at its forward end, as shown in Fig. 10, so that the gage 26^x may be moved as close as possible to the needle-hole 46, and thereby preclude the possibility of the goods slipping before being stitched. The plate is constituted in this form by bottom plate 47, extending under the arm 1^x and slide 29^x and having upturned flanges 48, through which the slide 29^x passes, and a top plate 49, which is substantially L-shaped, with a projection 50 on one side carrying the standard 36, and which plate 49 is secured to the bottom plate 47 by rivets 51 or other suitable means, and where the plate 49 passes over the slide 29^x and arm 7^x it is arched, as shown at 49^a, and through these arches are threaded two set-screws 52 53, which impinge the slide 29 and the arm 1^x, respectively, so as to hold them at their proper adjustment. The scale plate or strip 28^x for the gage 26^x is secured to the top plate 49 between the arches 49^a by means of a rivet 54, which may also pass through both plates 47 49. Where the gage 26^x passes under the arm 7^x it is provided on one side of the latter with an upturned guide-lug 55, which serves to guide the gage on one side, while the flange 27^x serves to guide it on the other side of arm 7^x. The gage itself in this form of the invention differs a little in the construction from that shown in Fig. 3, it being observed that the upturned flange 27^x in Fig. 10 extends from the edge of the arm 1^x to the forward end of the gage and that the slide or stem 29^x projects from the lower edge of the flange 26^x instead of from the end or corner of the gage, as in Fig. 3. This difference in form, however, is incidental to the difference in the method of producing the gage of a single piece and turning the guide-stem 29^x backwardly from the lower edge of flange 27^x.

It is quite obvious that while the crease marker or notch 4^x is shown as formed directly upon the creaser-arm 12^a in Figs. 10 to 16 it might nevertheless be carried on the

arm 7 in this form of the invention in the same way that it is carried on arm 7^x in the other form, and hence all other features of this modification are as applicable to the construction and arrangement of crease-notch, knife, and tuck-fold shown in Fig. 1 as they are to the form shown in Figs. 10 to 16.

Having thus described my invention, what I claim as new therein, and desire to secure by Letters Patent, is—

1. In a sewing-machine tucker, the combination with the plate and means for attaching the same to the sewing-machine, of two arms arranged one above the other and longitudinally adjustable on said plate but secured together and immovable relatively, a tuck-fold guide carried by the upper one and a knife carried by the lower one of said arms, a creaser for said knife and a fold-gage, common to both said knife and guide, and bearing the same relation to each other.
2. In a sewing-machine tucker, the combination with a knife, a creaser, a creaser-arm, and means for securing the tucker to the sewing-machine, of a pivoted operating-arm for oscillating said creaser-arm independently movable transversely thereof, locking-shoulders on said operating-arm, and a pivoted spring-dog adapted to engage said shoulders and attached to said creaser-arm for holding the latter steady.
3. In a sewing-machine tucker, the combination with a knife, a creaser and a creaser-arm, of an operating-arm extending transversely of said creaser-arm and movable independently thereof, locking-shoulders on said operating-arm, a friction-dog adapted to engage said shoulders, attached to said creaser-arm, a support for said operating-arm, a pivot connecting said dog and operating-arm to said support, and means for securing the tucker to the sewing-machine.
4. In a sewing-machine tucker, the combination of a plate, comprising an upper plate formed with an arch or upward bend, a knife, a knife-arm passing under said arch, means for supporting said knife-arm on one of said plates, a set-screw threaded through said arch and impinging said arm, a creaser, means for operating said creaser, and means for securing the plate to the sewing-machine.
5. In a sewing-machine tucker, the combination with means for securing the same to the sewing-machine, a knife and a creaser, of the plate comprising an upper plate formed with two upper bends or arches and a lower plate located below said upper plate and secured thereto, a knife-arm passing through one of said arches, a set-screw threaded in the latter said arch and impinging said arm, a gage comprising a stem passing through the other of said arches, and a set-screw passing through the latter arch and engaging said stem.
6. In a sewing-machine tucker, the combination of the plate, means for attaching the same to the sewing-machine, a knife, a creaser, a flexible creaser-arm, an operating-arm having locking-shoulders and adapted to act upon said creaser-arm, a laterally-deflectable spring-dog for engaging said shoulders adapted to rest upon said plate, a pivot connecting said tucker-arm and dog to the tucker and an extension on said dog through which said creaser-arm passes.
7. In a tucker, the combination with a knife and a creaser, of a tuck-fold guide arranged above the edge of the knife so as to engage the edges of the tucks while the latter are on the upper side of the goods, and a single-fold gage for both the knife and the fold-guide, arranged opposite said guide for engaging the apex of the fold of the goods.
8. In a tucker, the combination with a knife, a creaser and a tuck-guide arranged adjacent to and below the edge of the knife, of a tuck-fold guide arranged above the edge of the knife but in line therewith and with said first guide, and a gage arranged opposite said guides for engaging the apex of the fold of the goods while such fold is being stitched.
9. In a tucker, the combination with a knife and a creaser, of a fold-gage adapted to engage the apex of the fold being stitched, and a tuck-fold guide arranged opposite said gage and turned downwardly to engage the edges of the tucks while on the upper side of the goods, and bearing the same relation to said gage as said knife, whereby the one gage serves for both the knife and the fold-guide.
10. In a sewing-machine tucker, the combination with the plate, and means for attaching the same to the sewing-machine, a knife, a creaser for said knife and a tuck-fold guide, of a longitudinal scale-bar arranged below said fold-guide and adjustably secured to said plate and common to and permanently connected with said knife, creaser and guide and adjustable in unison therewith.
11. In a sewing-machine tucker, the combination with the plate, means for attaching the same to the sewing-machine, a knife, a creaser for said knife, and a tuck-fold guide, of a longitudinal scale-bar arranged below said fold-guide and adjustably secured to said plate and common to and permanently connected with said knife, creaser and guide and adjustable in unison therewith, and a fold-gage common to said knife, creaser and guide and adjustable along said scale-bar.
12. In a sewing-machine tucker, the combination with the plate, means for securing the same to the sewing-machine, and two horizontal arms arranged one above the other and slidably connected to said plate, of a knife secured to one of said arms, a creaser for said knife secured to and movable with said arms

as the same slide with relation to said plate, a fold-gage attached to said plate, and a fold-guide secured to the under side of the upper one of said arms and located the same distance from said gage as said knife, whereby the same gage serves for both the fold-guide and the knife.

13. In a tucker, the combination with a knife and a creaser, a tucker - plate comprising means for attachment to the sewing-machine,

an arm projecting from said plate, a tuck-fold guide inverted on the said arm and projecting downwardly and toward said plate for engaging the edges of the tucks on the upper side of the goods, and a fold-gage for engaging the apex of the fold being stitched.
